(57) **CLAIM**

I claim the ornamental design for an inflatable display screen, as shown and described.

DESCRIPTION

FIG. 1 is a perspective view of an inflatable display screen showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken lines show in the figure are included for the purpose of illustration portions of the inflatable display screen and form no part of the claimed design.
